Application May 19, 1933, Serial No. 671,792

5 Claims. (Cl. 206—38)

This invention relates to containers for cigarettes and more particularly boxes made of metal and generally designed to hold about fifty cigarettes. These boxes are made in immense quantities every year and involve a large expenditure in labor and material. Furthermore much effort is devoted to making them attractive in appearance, and in themselves they constitute a valuable advertising medium for the brands of cigarettes contained in them. At the present time they are discarded and are of no further use when emptied of their contents.

An object of the present invention is to extend the utility of these boxes and to further enhance their advertising value by the provision of means to adapt them for ash trays and for supporting lighted cigarettes when the boxes are wholly or partially emptied of cigarettes. The usefulness of the boxes is thus prolonged and an incentive is created to retain them with a consequent continued advertising appeal.

This and other objects are secured by the provision of a cigarette rest within each box of cigarettes of such a conformation and design as not to interfere with the packaging of the cigarettes or to cause any damage to the packed cigarettes. Preferably also the rest is perforated along the line of contact with a cigarette so as not to transmit heat from a lighted cigarette placed thereon to other portions of the cigarette as will hereinafter appear.

In the accompanying drawing illustrating several embodiments,

Fig. 1 is a perspective of a cigarette box with one form of a cigarette rest applied thereto;

Fig. 2 is a plan view of the blank from which the rest shown in Fig. 1 is bent;

Fig. 3 is an end view of the blank of Fig. 2;

Fig. 4 is a side view of the blank of Fig. 2;

Fig. 5 is another perspective of a box illustrating the application of two other forms of the rest;

Fig. 6 is a plan view of the blank for one of the rests shown in Fig. 5; and

Fig. 7 is a plan view of the blank for the other form of rest shown in Fig. 5.

As ordinarily made a box 10 for holding cigarettes is shallow, and the cigarettes are divided into two portions, separated by a folded paper or other material to form a partition. In the embodiment shown in Fig. 1, a partition 11 is substituted which can be of tin-plate (the same material as the box) or of other suitable material secured to the box. The partition is used as a support for a cigarette rest 12 when the box is emptied of cigarettes, thus converting the box

into an ash tray with cigarette supports 13 and 14 for lighted cigarettes. The rest 12 is separable from the partition, and is made from a blank as shown in Figs. 2, 3 and 4 comprising the supporting portions 13 and 14 connected by a bridging portion 15. The rest can be made of thin sheet metal so as to be readily folded on the dotted line 16, and again bent on the lines 11, 18 into the shape shown in perspective in Fig. 1 to form the saddle section 19. Preferably the rest is given an arcuate cross section as illustrated in the end view, Fig. 3, so as to hold a cigarette in place. The portions 13 and 14 have perforations 20, 21 forming cross bars 22 so proportioned and spaced that heat from a lighted end of a cigarette is not transmitted to other portions of the cigarette to any appreciable extent.

As supplied with a box filled with cigarettes, the rest 12 is preferably in the bent form and placed in an inverted position with the saddle portion 19 in contact with the partition 11 and the arcuate ends 13 and 14 overlying cigarettes in the box. As the curvature of the ends corresponds more or less with that of the underlying cigarettes there is no appreciable distortion of the cigarettes, and the saddle portion prevents endwise slippage. The rest, however, can be placed in the box in the blank form and readily bent into shape by the user.

Another embodiment is shown in Figs. 5 and 6. The blank 30 shown in Fig. 6 has an attached portion 31 which when folded on the line 32 and bent on the line 33 forms a saddle portion 34 to clip on the side of a box. With this form no provision need be made for a middle partition, though if there be such a partition it can be clipped on the partition instead of a box end. It is preferably supplied in the finally bent form, the saddle 35 being inverted and slipped into a filled box in contact with a box end and the portion 30 overlying the cigarettes. It can also, however, be placed in the box in the blank form.

Another form, shown in blank in Fig. 7 and in perspective in Fig. 5, is intended to be permanently attached to the box. For this purpose the blank 40 has a tongue 41 that can be bent on the lines 42, 43 to form sections 44, 45. The section 45 is soldered or otherwise fastened to the lid or to the bottom of the box so as to bring the rest into contact with the box. For use the rest can be elevated from the lid or bottom by lifting the rest and then bending it back on the line 42 so that the portion 44 extends vertically from the lid.

As heretofore explained it is intended that the

embodiment 12 and 30 be supplied loose in a box and placed on top the cigarettes when a box is filled in an inverted position with the saddle tucked next to a partition or the end of a box. 5
5 When the box is emptied or partially emptied of cigarettes (as for example the removal of the cigarettes on one side of a partition) the rest is put in place by clipping the saddle on the partition or the box end. This then converts the box 10 or a portion of it into an ash tray with a support for a lighted cigarette within the tray. In the embodiment 40 which is permanently attached, the rest need not necessarily be bent up from the plane of the lid but it is found preferable to do 15 so for use.

The perforations provided in the rest prevent direct transmission of heat along a lighted cigarette lying in the rest. The perforations are preferably of a width that ensures non-contact 20 longitudinally between the rest and the cigarette, and the separating cross bars are made sufficient in number to insure proper support for the cigarette.

While primarily intended for use with the customary boxes made from tin plate, the rest herein disclosed can be supplied and used with boxes made of other materials, such as cardboard which has a fireproofed surface so that a box so made 25 can be safely used as an ash receiver.

30 I claim:

1. Cigarette container comprising in combination a box consisting of a receptacle of a conformation for holding cigarettes for transportation and a lid therefor and a cigarette rest consisting of a substantially straight elongated metal strip of arcuate cross-section for contacting cigarettes and permitting closure of the lid when the box contains cigarettes without injury to the latter, said strip including means formed integral 35 therewith and adapted to support the strip by the box in spaced relation from the walls of the box and within the confines of the box whereby a lighted cigarette placed on said rest can be maintained out of contact with the box in a manner to deposit any ashes falling therefrom in the box.

2. Cigarette container comprising in combination a box consisting of a receptacle of a conformation for holding cigarettes for transportation 50 and a lid therefor and a cigarette rest consisting of a substantially straight elongated metal strip of arcuate cross-section for contacting cigarettes and permitting closure of the lid when the box contains cigarettes without injury to the latter, said strip including means formed integral therewith and adapted to support the strip by the box in spaced relation from the walls of the box and within the confines of the box whereby

a lighted cigarette placed on said rest can be maintained out of contact with the box in a manner to deposit any ashes falling therefrom in the box, the cigarette-supporting portion of the rest being perforated along a line of contact with a cigarette to prevent undue transmission of heat by the metal strip along the length of a lighted cigarette. 5

3. Cigarette rest for a cigarette box consisting of a receptacle of a conformation for holding 10 cigarettes for transportation and a lid therefor, said rest consisting of a substantially straight elongated metal strip of arcuate cross-section for contacting cigarettes and permitting closure of the lid when the box contains cigarettes without 15 injury to the latter, said strip including means formed integral therewith and adapted to support the strip by the box in spaced relation from the walls of the box and within the confines of the box whereby a lighted cigarette placed on the 20 rest can be maintained out of contact with the box in a manner to deposit any ashes falling therefrom into the box.

4. Cigarette rest for a cigarette box consisting of a receptacle of a conformation for holding 25 cigarettes for transportation and a lid therefor, said rest consisting of a substantially straight elongated metal strip of arcuate cross-section for contacting cigarettes and permitting closure of the lid when the box contains cigarettes without 30 injury to the latter, said strip including a saddle portion integral therewith and adapted to support the strip by the box in spaced relation from the walls of the box and within the confines of the box whereby a lighted cigarette placed on the 35 rest can be maintained out of contact with the box in a manner to deposit any ashes falling therefrom into the box.

5. Cigarette rest for a cigarette box consisting of a receptacle of a conformation for holding 40 cigarettes for transportation and a lid therefor, said rest consisting of a substantially straight elongated metal strip of arcuate cross-section for contacting cigarettes and permitting closure of the lid when the box contains cigarettes without 45 injury to the latter, said strip including a saddle portion integral therewith and adapted to support the strip by the box in spaced relation from the walls of the box and within the confines of the box whereby a lighted cigarette placed on the 50 rest can be maintained out of contact with the box in a manner to deposit any ashes falling therefrom into the box, the cigarette-supporting portion of the rest being perforated along a 55 line of contact with a cigarette to prevent undue transmission of heat by the metal strip along the length of a lighted cigarette.

IRVING M. PLANT.
